UNITED STATES PATENT OFFICE.

FRANK D. SHEPHERD, OF SALT LAKE CITY, UTAH.

PUPPET-VALVE FOR GAS-ENGINES.

1,330,045.

Specification of Letters Patent.

Patented Feb. 3, 1920.

Application filed May 4, 1918. Serial No. 232,592.

To all whom it may concern:

Be it known that I, FRANK D. SHEPHERD, of Salt Lake City, county of Salt Lake, and State of Utah, have invented a certain new and useful Improvement in Puppet-Valves for Gas-Engines, and do hereby declare that the following is a full, clear, and exact description thereof.

My invention relates to internal combustion engines, and in particular to the valves and valve actuating mechanism, and my object is to so improve the construction that cost of manufacture will be lessened, and at the same time the strength of the parts increased, and such wear of the valve head or its seat as will impair its efficiency, be prevented, and to this end, and for attaining other objects that will be apparent to those skilled in the art, my invention consists in the puppet valve and its actuating mechanism constructed substantially as herein-after specified, and claimed.

In the annexed drawings—

Figure 1 is a view in vertical section through one of the valve mechanisms, embodying my invention;

Fig. 2 is a view in side elevation, of a four cylinder T-head gas engine, embodying my invention;

Fig. 3 is a view, like Fig. 1, showing another embodiment of my invention; Fig. 3^a is a detail enlarged view showing the ball bearing between disk and stem.

Fig. 4 is a similar view of yet another embodiment of my invention;

Fig. 5 is a detail top plan view of the lower, spring-engaging disk shown in Fig. 4.

Giving a detail description of the construction shown in the drawing, the engine shown is of the T-head type with four cylinders 10 and connected with said head there are as many puppet valves, as, in the judgment of the designer it is proper, or desirable to employ, sixteen in the case shown, but for the purpose of disclosing my invention to those skilled in the art it is not necessary to show and describe more than one valve mechanism, which thus is to be taken as representative, or typical for both the intake 45 and the exhaust, and for as many as it may be desirable, or expedient to employ. There may be either single or double intake and exhaust valves, on both sides of the engine. My invention, as will be evident, has to do 50 with the valve construction and not with the number employed (although its construc-

tion is such as to render unnecessary multiplication of the number); nor is my invention concerned with the particular type, or construction of the engine. In the engine 60 head eccentric to the cylinder, I provide an internally threaded opening 12 which extends from the outer end of the head into the port 18, which is controlled by the valve mechanism, for which purpose, directly in 65 line with said opening 12 and on the opposite side of the port it has a beveled seat 14 for the puppet valve 15 whose face, or rim is correspondingly beveled so that it closely, and in a gas tight manner, fits the seat. 70 Screwed in said hole 12 is one end of a cylindrical shell 16, a gas tight joint being formed between a shoulder on said shell and the outer side of the cylinder head by an interposed washer, or gasket 17. The outer 75 end of said shell is closed in a gas tight manner by a cap 18 which is screwed over said outer end and a gas tight joint formed by a washer, or gasket 19 clamped between the cap and a shoulder, or bearing on the 80 shell. At the opposite inner end of the shell it is closed save for a central hole 20 through which passes, with a sliding fit, a stem 21. Said stem extends from the valve end into the chamber in said shell and within the 85 chamber it has a flange, or head 22 of substantially the diameter of the chamber, and between said head and an abutment, or bearing surface is interposed an expansive coil spring 23, which by pressure on the valve 90 transmitted through said head and stem yieldingly holds the valve to its seat from which it is lifted by the usual lifter cam 24. The head 22 is in the form of a disk separate from the stem 21, but is seated on the 95 upper end of the latter by having a socket 25 in its underside into which snugly fits the upper end of the stem 21. Upon its upper side said disk has a central boss 26 that projects into the lowest coil of the spring 100 23, and on its periphery a series of radial notches 220 to permit the ready passage of air so as to prevent movement of the valve being hindered by air pressure. As the disk is a separate piece from the stem, the disk 105 can be drop-forged or stamped out, and costly machine work is thus avoided, and, hence, can be easily and cheaply made, and as the stem need be but a simple straight bar with a flat top its cost of manufacture 110 is small, especially as compared with a stem having a special formation at its top and

requiring machine work. As shown in Fig. 2, the stem is separate from the valve head, while in Figs. 3 and 4 it is integral therewith. The loose connection between the 5 stem and the disk, especially when the integral valve head and stem construction shown in Figs. 3 and 4 is employed, permits the free turning of the valve head, as hereinafter more fully described, as its turning 10 movement meets with less resistance than would be the case if the disk also had to turn. To facilitate this turning movement, an anti-friction ball 210 may, as shown in Fig. 3, be interposed between the top of the 15 stem and the bottom of the disk, said ball being seated in a recess 27 in the top of the stem. And, as shown in Figs. 3 and 4, the disk may have a central hole 28 leading from its top to the ball or the top end of 20 the stem, for the supply of a lubricant to the contacting surfaces on disk and stem, and prevent cutting or grinding of the surfaces of the disk socket 25.

The recess 27 for the ball may be made 25 with flat sides to receive a turning tool for grinding the valve on its seat, or as shown in Fig. 4, a slot 211 may be provided in the top of the stem for that purpose.

The guide hole for the stem 21 may, as 30 shown in Fig. 4, be provided in a bushing 29 of different material from the shell 16, and tightly fitting and secured within a hole in the latter below the spring chamber or the shell 16 may have a hole just large enough 35 to fit the stem. And, preferably, in either case, a plurality of annular grooves 30 is provided in said guide opening to provide pockets for lubricant and form a seal to prevent leakage of gas around the stem. By 40 making said grooves in the walls of the guide openings instead of in the stems, the latter are not weakened, but every advantage from the use of grooves, is secured. Some valve stems are so small that it would 45 be objectionable to groove them, and that is my reason for placing the grooves in the guide wall.

As shown in each of Figs. 1, 3 and 4, an 50 oiling hole 31 is provided through the top of the cap 18, at its center, which may be closed by a removable screw plug 32, as shown in Figs. 1 and 4, a gasket 320 being placed under the plug head to make a gas-tight joint, or, as shown in Fig. 3 it may be closed by 55 a disk 33 within the spring chamber, which engaged by the upper coil of the spring, is held tight against the inner surface of the cap around the hole 31,—a gas tight joint being assured by a ground joint between 60 contacting sides of cap and disk. By pressing down the disk, as by the nozzle of an oil can, the oil will flow over the disk, and be distributed in all directions, and pass down around the disk, such passage being 65 promoted by radial notches 34 in the periph-

ery of the disk 33. On its inner side the disk has a boss or projection 35 that loosely fills the spring coils, and is of such length as to serve as a filler of space in the casing 16, and thus diminish the unoccupied volume 70 in the shell and, hence, the room for gas that might, perchance, leak by the stem 21. As no part of the stem 21 projects above the disk 22, it is unnecessary to recess the underside of the filler boss, but the same may 75 be flat, and, hence, economy of construction is secured. The disk and its boss may be used in the construction shown in Figs. 3 and 4, or merely the boss 36 employed, as shown in said Figs. 3 and 4, which projects 80 inward from the cap, and serves merely as a spring centering device, or as a filler.

The cap 16, as shown in Fig. 3, may have an angular socket 37 in its top to receive a turning tool; or, as shown in Fig. 1, may 85 have radial holes 38 in its side, to receive a spanner wrench or a rod; or, as shown in Fig. 4, it may have spaced lugs 39 between which can be placed a bar for turning it. In all these ways the quantity of metal required for the cap can be lessened, and thus 90 cheapness and lightness obtained, but without sacrifice of proper strength. Additional lightness is obtained in the cap shown in Fig. 1 by a recess 40 in its top to receive the 95 head of the oil plug 32.

Although I show a single spring in the shell 16, it is to be understood that more 100 can be used, if desired.

It is also to be understood that the various 100 features of my valve seating mechanism may be differently combined.

What I claim is:

1. The combination of an engine cylinder having a valve-controlled passage with a 105 valve seat, a puppet valve, a shell or container, a spring in said container, a stem reaching from the valve into said container, and a spring-engaging disk in the container separate from the stem, the spring and stem 110 engaging the disk on opposite sides, the stem terminating short of the side of the disk engaged by the spring.

2. The combination of an engine cylinder having a valve-controlled passage with a 115 valve seat, a puppet valve, a shell or container, a spring in said container, a stem reaching from the valve into said container, and a spring-engaging disk in said container 120 separate from the stem and having in its underside a stem receiving socket, the stem terminating in said socket below the plane of the top of the disk.

3. The combination of an engine cylinder having a valve-controlled passage with a 125 valve seat, a puppet valve, a shell or container, a spring in said container, a stem reaching from the valve into said container, and a spring-engaging disk in said container 130 separate from the stem and having

in its underside a stem receiving socket, an oil hole being provided in said disk leading into said socket.

4. The combination of an engine cylinder having a valve-controlled passage with a valve seat, a puppet valve, a shell or container, a spring in said container, a stem reaching from the valve into said container, a spring-engaging disk in said container separate from the stem and having in its under side a stem receiving socket, and a ball bearing between the disk and the stem.

5. The combination of an engine cylinder having a valve-controlled passage with a valve seat, a puppet valve, a shell or container, a spring in said container, a stem reaching from the valve into said container, a spring-engaging disk in said container separate from the stem and having in its under side a stem receiving socket, and a

cap having a normally closed oiling hole, secured to the outer end of said shell and which supports the thrust of the spring.

6. The combination of an engine cylinder having a valve-controlled passage with a valve seat, a puppet valve, a shell or container, a spring in said container, a stem reaching from the valve into said container, a spring-engaging disk in said container separate from the stem and having in its under side a stem receiving socket, and a cap having a normally closed oiling hole, secured to the outer end of said shell and which supports the thrust of the spring, said cap being recessed on its outer surface to lighten it and for engagement by a turning tool.

In testimony that I claim the foregoing I have hereunto set my hand.

FRANK D. SHEPHERD.
